UNITED STATES PATENT OFFICE.

JOHN GOOD, OF BROOKLYN, NEW YORK.

INTERNAL-COMBUSTION ENGINE.

1,177,698.

Specification of Letters Patent.

Patented Apr. 4, 1916.

Application filed April 28, 1914. Serial No. 834,902.

To all whom it may concern:

Be it known that I, JOHN GOOD, a citizen of the United States, residing at Brooklyn, in the county of Kings and State of New York, have invented the following described Improvements in Internal-Combustion Engines.

The improvement relates to an organization of rotary valve mechanism in internal combustion engines adapting such valves to resist high combustion temperatures and explosion pressures without impairment of function, and to perform long-continued efficient service without special or any care on the part of the user.

Notwithstanding their superior simplicity and general convenience of structure and operation rotary valves have not heretofore been adapted to combustion engines with the same degree of permanent efficiency as possessed by the ordinary puppet valve in the same relation. The reason for such shortcoming I have ascertained to lie in the difficulty of maintaining the necessary character of oil film between the meeting faces of the rotary member and its seat, particularly after the valve has become worn in service, and also the inability to avoid the disturbance that results from impairment of the film, in the process of heat-dissipation from the valve member to the surrounding heat-absorbing medium, or water-jacket. In prior rotary valves, disk and conical, the oil film tends to accumulate near the largest peripheral part and wear also takes place the most at that part because of the higher surface speed, while excessive friction and scoring is apt to occur at the part near the center, this being accompanied by local thermal expansions in that region due to such friction as well as to local exposure to flame, all of which combine to produce accelerating leakage and to curtail the useful life of the valve.

The object of my invention is to preserve the necessary film of oil between the meeting surfaces of valve member and seat under all conditions of use and wear, and thereby provide the uniform cooling of the said parts which is essential to permanent efficiency in a combustion engine. The means I have invented to this end provide a rotary or oscillatory valve structure of exceptionally long life, which equals the efficiency of the well known puppet but avoids its disadvantage, that it must be periodi-

cally ground to its seat, and which is conveniently and noiselessly operated and which, furthermore, need be no larger, port for port, than the puppet valve, besides possessing other advantages as respects its organization in the engine structure, as will later appear.

The principle of the invention and the best mode in which I have contemplated using the same, will be explained in the following detailed description in connection with the illustrative drawings, wherein—

Figure 1 is a partial end elevation of a combustion engine, with parts in section through the center of a valve mechanism embodying this invention. Fig. 2 is a bottom view of the valve proper of Fig. 1, showing the valve shaft in section. Fig. 3 is a horizontal section on line III—III of Fig. 4, with the valve removed to expose the valve seat. Fig. 4 is an axial section through the valve structure; and Fig. 5 is a section similar to Fig. 3, with the valve in place.

In accomplishing the objects above set forth, I provide the engine with a valve seat 1, which may be variously disposed but is herein shown as formed in the lower part of a lateral extension from the combustion chamber of the engine. The rotary valve member for this seat is marked 2 and is rotated by an upright valve-shaft 3, driven by the engine crank shaft 4, through a lay shaft 5 and suitable reduction gearing. In the case illustrated, the valve shaft is integral with the valve, as a spindle therein although it can be separately made and attached to the valve, if desired. The lay shaft 5 is inclosed in a crank-case 6, into which the valve spindle 3 projects and by which it may be supported. According to the number of port openings in the valve, the said shaft may be geared to drive the rotary valve member one or less revolutions for each four strokes of the piston 7, the engine being presumed to be 4-cycle. The meeting or seating surfaces of the valve 2 upon its seat 1 are curved both in their horizontal and vertical sections and both surfaces are alike. In the horizontal section such surfaces are circular with the axis of the valve as center, and in the vertical section the curve is concave and non-circular, the greatest degree of curvature being at the top and larger end, and the least near the bottom and smaller end, so that the seat-

ing portion of the valve member, when removed, resembles the surface of a truncated cone which has been turned down so as to have a diminishing taper from its large to its small end. The corresponding surface of the valve seat has the same shape and is formed upon a wall of the water-jacket structure having the same compound curvature and which is relatively thin in its cross-sectional dimension and of the same degree of thinness throughout.

The uniform thinness of the valve-seat wall, is a matter of importance to the object of my invention, since thereby the heat from the valve member has the shortest possible path of escape to the water-jacket. The described curvature of the said wall gives it considerable strength and rigidity, after the manner of an arch, and therefore permits it to be made thinner than would otherwise be possible. The same curvature and thinness likewise provides space in the water-jacket for a relatively large volume of water all around the valve and for proper circulation thereof, without unduly enlarging the engine casting. The valve member 2 is formed hollow or shell-like, and its wall is of uniform cross-sectional dimension and no thicker than the seat wall with which it is in contact (through the oil film) and to which it is generally parallel. The interior of the valve member is open to the interior of the combustion chamber and the gaseous medium flowing to or from the chamber passes axially through the large end of the valve and also outwardly through the port opening 9 cut in the curved wall thereof. The longitudinal boundaries of this opening, or openings if there are more than one, lie in planes which are radial the axis of the valve. The corresponding, fixed port opening 10 pierces the water-jacketed valve-seat wall at an upward angle with reference to the axis of the valve, or generally perpendicular to the curved side of the valve seat, and in this manner the pipe or manifold connection 11 becomes disposed at a downward inclination from the side of the combustion chamber and the combustible or combustion gases may thus enter or leave the engine in a fairly straight path. The port opening 10 is likewise formed between planes which are radial or intersect the axis of the valve, and it may be noted at this point that the area of each opening may be larger than the area of lift opening of an ordinary puppet valve of the same overall diameter.

The preferred curvature of the seating surface conforms to the geometrical curve known as the equitangential tractrix, and the said seating surface is a surface of generation of a tractrix curve revolved about its axis. Such a surface, as above stated, has maximum curvature near the top or large

end of the valve and least curvature near the bottom or small end, and when provided as the meeting or bearing surface between two axially thrusting bodies, such as parts 1 and 2, has heretofore been determined to give substantially equal wear under certain conditions of contact and contacting materials, so that such bodies will tend to wear fairly true to their original tractrix curvature. I have ascertained that the particular relationship of pressures to velocities in different zones of surfaces so contacting, namely, the fact that, in such contacting surfaces, the surface velocity is slow where the pressure is high, and high where the pressure is low, can be utilized to establish substantially equal distribution of the oil between such surfaces and in such manner as to form a continuous film throughout, in spite of the interruption to such surfaces represented by the port openings, while the tendency of the surfaces to wear true is utilized to preserve the said relationship. The uniform thinness of the walls of the valve-member and the valve-seat, and the consequent proximity of the highly heated side of the valve member to the water-jacket, as above explained, permit the said oil film to be maintained safe against interruption by burning, and thus adapts the valve as a whole to resist the effects of high temperature. The thermal contact thus established between the valve member and its seat not only avoids the local expansions caused by hot spots in other valves, but tends to maintain the valve as a whole at a constant temperature and in a fixed relation to that of the water-jacket, that is to say, the dissipation of heat is so prompt and rapid that the valve temperature varies only within relatively narrow limits and in any case rises and falls in practically exact accordance with the rest of the engine casting, being thus particularly suited for machines operating under high temperatures and pressures, as for example the Diesel engine. It should be stated also that the valve member and its seat are both made of cast iron, or at least of the same kind of material, so that such expansion as does take place is substantially equal in each part and is thus compensated.

The presence of the port openings through the curvature of valve and seat diminishes the extent of contact, peripherally considered, in the waist portion of the valve and produces tendency toward excessive wear and reduction of seating pressure in the transverse zone of both of these parts. If the said parts had no openings the pressure value would remain unchanged under progressing wear, other conditions being favorable, but the removal of a part of the rubbing surface of one zone throws a greater friction on the remainder and thereby in-

creases the rate of wear in that zone. This in time may seriously impair the thermal contact between the valve and seat and produce leakage. Moreover, when the valve 5 contains but a single port, as in the case taken for illustration, the wear occurs more on one side than the other, giving the valve a tendency to wear askew to its axis. Both of which tendencies are apt to develop leakage and imperfect operation unless compensated. I have provided such compensation in simple form as follows: Diametrically opposite to the port 9 I provide a dummy port or relieved area 11 (see Fig. 2) and in 10 the valve seat directly opposite the port opening 10, a similarly relieved area 12, both of these being equal in size and in shape and general relationship to the area of the port openings 9 and 10, and in the same zone 15 or relationship to the curvature of the rubbing surfaces as a whole. Where the valve is double ported, one or both of these dummy ports could be actual ports if desired, according to the timing. Their purpose in 20 either case is to balance the wear on opposite sides of valve and seat to prevent the valve from wearing askew to its axis.

Above the zone line *a* (Fig. 2) of the top boundary of the port opening 9 (or 11) I 25 provide two diametrically opposite relieved spaces 14 extending from such line about half-way to the top of the valve, and also two similar relieved spaces 13 out of radial line with the spaces 14 extending from the 30 level of the top boundaries of the latter to the top of the valve, these spaces 13 being also diametrically opposite each other. Below the zone line *b* of the bottom of the port opening, I provide two diametrically 35 disposed recesses 24 extending from such zone line about half way to the lower end of the seat, and two similar recesses 25 out of radial line with 24 and extending the rest of the way, to the end of the seat. In the valve 40 seat (Fig. 3) I provide similar opposite recesses 15 above the zone line of the opening 10 and corresponding in area to the aggregate areas of relieved spaces 13 and 14 on the valve member, and below the port opening 45 two further recesses 16, aggregating the areas of the recesses 24 and 25 in the valve member. The vertical boundaries of each of these relieved spaces, preferably lie in planes which are radial to the axis of the 50 valve and the angle subtended between such planes by each recess is equal to that subtended by the port openings 9 and 10. This disposition of the relieved areas preserves the same effect in respect to the wear of the 55 valve as if no openings were present therein at all, and the valve when in use therefore exerts a pressure upon its seat, preserving a uniform, continuous oil film thereon, while the recesses themselves serve as small supply pockets for oil.

The distribution of the relieved areas may be effected in various manners and varied practically indefinitely, but they should be preserved symmetrical to the axis of the valve, and in lateral extent, should not exceed the angle of the port openings as above described. The distribution will, of course, avoid the formation of a leak path in any position, and in the present case this is prevented by the staggered arrangement shown. 70 The deposit of lubricant at upper part of the valve will work readily into the seat and but very little lubricant is required since all of the surface exposed to flame is closely proximate to the water-cooled valve seat as 75 above pointed out, and practically no oil is burned while on the seat.

While I may use a special oil supply to the valve, I have found in practice that it is quite sufficient under ordinary conditions to 80 rely for lubrication simply on the oil that works up the wall of the cylinder into the combustion chamber, which fact is an indication of the permanency of the oil film in my new valve. It is not possible in any 85 other form of rotary valve of which I am aware to rely on so small a supply of lubricant. The piston 7 may be lubricated by the splash from the crank casing 6 and together with such casing constitutes a means for supplying oil to the valve, but this means, as stated, may also be supplemented by auxiliary oil supply devices if desired.

The interior pressure in the combustion chamber, from the explosion or compression of the charge, serves to keep the valve seated during part of the engine cycle, in the intervals, a spring 18 keeps it seated with sufficient force to resist the counter-pressure developed by the suction stroke of 100 the piston, being of course aided by the gravity of the spindle 3 and gear 17 thereon. This non-positive means for seating insures the proper operation of the valve since it keeps the rotary member in uniform thermal contact with its seat after wear has taken place, and prevents the development of looseness of the valve member such as would be likely to impair the oil film. The spring 105 18 thrusts against a ring washer 19 below the valve seat and upon a collar 20 set-screwed to the valve shaft 3, the spring and collar being inclosed and protected by a screw cap 21 which is screwed to the engine structure fitting loosely on the shaft 3.

In Fig. 4 the tractrix curvature of the valve member 2 is extended below the valve seat and is partly surrounded by the screw cap just mentioned, but this is merely for the purpose of illustration of the said curve 110 in the present case and need not be so formed in practice. The lower part of the seat below the valve port serves also as a stuffing box preventing escape of pressure at the 115 point of drive and in order that the proper 120

seating of the valve shall not be disturbed by the driving connections, I make the spindle or shaft 3 relatively slender and several times the length of the valve, so that it is 5 flexible and thus able to accommodate itself to the position of the valve while in rotation, without imparting lateral pressure thereto which would disturb the uniformity of the oil film and hence interfere with the cooling 10 effect. The shaft or spindle 3 may be as thin as consistent with the work it has to perform. As above pointed out, the valve may operate in the lower wall of a lateral extension of the combustion space of the engine, the common location of the puppet valve in such engine, and like the puppet valve can be removed vertically through the top hand-hole when the cover 23 has been unscrewed. It may also be disposed in other 15 relations to the engine, either as exhaust or inlet or both, as shown in another application, and it will be understood in general that the invention is not confined to embodiment in the specific form shown in these 20 drawings, but that various modifications, changes in proportions and arrangements of parts, can be resorted to without departing from the principle of the invention above explained.

30 I claim:

1. The combination with the combustion chamber of an internal combustion engine, of a hollow, taper-curved, rotary valve-member having its larger end exposed to the 35 pressure in said chamber, and its smaller end connected to be driven by the engine crank-shaft, a valve-seat for such valve of correspondingly tapered form, the vertical section of the meeting surfaces of valve-member and 40 seat having greater curvature at the larger end of the valve-member than at the smaller, and valve-port openings through said taper-curved surfaces forming a passage through the larger end of the valve member to or 45 from the said combustion chamber.

2. The combination with the water-jacketed combustion chamber of an internal combustion engine, of a taper-curved, rotary valve-member having its larger end exposed to the pressure in said chamber, and its 50 smaller end connected to be driven by the engine crank-shaft, a valve-seat for such member formed on a wall of substantially uniform cross-section, which is surrounded by the cooling medium of the engine water-jacket, the longitudinal section of the seating surface of said valve and seat having greater curvature at the larger end of the 55 valve member than at the smaller, whereby 60 an oil film between said member and seat is maintained continuous and uniformly cooled, and port openings through the taper-curved 65 surfaces of the seat and valve-member communicating through the latter with the combustion chamber.

3. The combination with the combustion chamber of an internal combustion engine of a hollow, taper-curved valve-member connected to be driven by the engine crank shaft and having its larger end and hollow interior exposed to the combustion temperature in said chamber, a valve seat for said member formed on a wall through which the heat of said member is abstracted, the longitudinal section of the meeting surfaces of member and seat having greater curvature at the larger end than at the smaller, whereby a continuous oil film is maintained over the seating surfaces of said member and seat, port openings in said surfaces and a spring 75 holding said member against its seat.

4. The combination with the combustion chamber of an internal combustion engine, of a hollow, taper-curved, rotary valve-member connected to be driven by the engine 80 crank-shaft, a valve-seat for such member incorporated in the structure of the engine, the meeting surfaces of said valve-member and seat conforming to the surface of generation of a tractrix revolved upon its axis, 85 whereby a continuous oil film is maintained on said valve seat, a spring urging said valve member upon its seat, and port openings formed in said valve and seat forming a communication through the valve to said 90 chamber.

5. The combination with the combustion chamber of an internal combustion engine, of a taper-curved, rotary valve-member having its smaller end connected to be driven by the engine crank-shaft and its larger end subjected to the pressure in said chamber, a valve-seat for such member incorporated in the water-jacketed structure of the engine and surrounded by the liquid therein 100 throughout the whole of its seating area, the meeting surfaces of said valve-member and seat conforming to the surface of generation of a tractrix revolved upon the axis of said valve member, whereby permanent thermal 105 contact is maintained between the member and its seat.

6. In an internal combustion engine, the combination of a valve seat, a rotary valve-member therefor, the engaging surfaces of 110 said member and seat conforming to the surface of generation of a tractrix revolved about its axis, port openings through the seat and the large end of the valve member, and a driving spindle on the small end of 115 the valve member, said spindle being several times the length of said seat and constituting a laterally flexible driving means for the rotary member.

7. In an internal combustion engine, the 120 combination of a valve seat formed in the engine structure, and a rotary valve-member, the engaging surfaces of valve-member and seat conforming to the surface of 125 generation of a tractrix revolved about its 130

axis, means for abstracting heat from said valve seat, non-positive means for urging the member upon the seat and registering port openings formed in the wall of said member and seat.

8. In an internal combustion engine, the combination of a valve seat and rotary valve member therefor, the meeting surfaces of member and seat conforming to the surface of generation of a tractrix curve, a port opening in said parts extending through one side of said generated surface, means for rotating the valve member on its seat and means for balancing the wear on said valve to prevent its wearing askew to its axis.

9. The combination in a combustion engine of a rotary valve-member and valve-seat engaging each other in the surface of generation of a tractrix curve and having port openings through such surface and the larger end of the valve member, communicating with the combustion chamber of said engine, the meeting surfaces of said valve and seat being provided with relieved areas symmetrically disposed with reference to the axis thereof and adapted to preserve the wear symmetrical on all parts of the valve member and seat, and engine-driven means which are self-accommodating to the axis of said valve, for driving the same,

10. The combination of a rotary valve-member and valve-seat engaging each other in the surface of generation of a tractrix curve and having port openings through such surface and the larger end of the member, the meeting surfaces of said member and its seat being provided with relieved areas disposed above and below the zone of the port openings.

11. The combination of an internal combustion engine having a lateral extension of its combustion chamber and a vertically curved valve seat formed in the wall of such extension, a rotary valve member engaging such seat, the curvature thereof conforming to the surface of generation of a tractrix revolved about the axis of said valve, port openings through said seat and member and communicating through the larger end of the valve member with the said combustion chamber, an upright valve shaft connected with the smaller end of the valve member and driven by the engine crank shaft, and a spring urging the valve member toward its said seat.

12. The combination with the combustion chamber of an internal combustion engine, of a taper-curved rotary valve member therefor, a cooled similarly taper-curved valve seat for such member incorporated in the engine structure and symmetrically

sustaining the pressure of the valve member thereon, the curvature of the seating surfaces of said valve member and seat being greatest near the larger end and diminishing toward the smaller end, means whereby oil is supplied to said surfaces, registering port openings intersecting the said curved surfaces of said valve and seat, and means connected with the engine crank-shaft for driving said valve member in phase therewith.

13. The combination with the combustion chamber of an internal combustion engine, of a rotary valve member therefor, a cooled seat for such member, means for supplying oil to the seat, the meeting surfaces of said member and seat being disposed in the surface of generation of an equitangential tractrix revolved upon its axis, means for holding the said valve member to its seat, registering port openings in said member and seat intersecting the said curved surfaces thereof, and means for rotating the valve member in phase with the engine.

14. The combination in an internal combustion engine, of a rotary taper-curved valve-member, a valve seat therefor, the longitudinal section of the seating surfaces of said member and seat having greatest curvature near the larger end of said valve member, diminishing to least curvature near the smaller end thereof, registering port openings leading through said seating surfaces, and means for driving the valve member, said means being self-accommodating to the axis of said member and adapted to drive the same without disalignment thereof from said axis.

15. The combination in an internal combustion engine of a hollow rotary taper-curved valve member, the wall whereof is of substantially uniform thickness throughout the whole of that portion of said member which forms its seating surface, a similarly taper-curved valve seat for said member, the wall whereof is of uniform thickness co-extensively with its seating surface, means surrounding said wall for abstracting heat therefrom, the meeting surfaces of said member and seat being disposed in the surface of generation of a tractrix curve revolved upon its axis, means for supplying oil to said surface, and means for driving said valve without deflecting it from its axis.

In testimony whereof, I have signed this specification in the presence of two witnesses.

JOHN GOOD.
